(57) **CLAIM**

The ornamental design for a vacuum cleaner upper portion, as shown and described.

DESCRIPTION

FIG. 1 is a perspective view of a vacuum cleaner upper portion showing our new design;

FIG. 2 is a front elevational view thereof;

FIG. 3 is a right side elevational view thereof;

FIG. 4 is a left side elevational view thereof;

FIG. 5 is a rear elevational view thereof; and,

FIG. 6 is a top plan view thereof.

The parts shown in broken lines in all of FIGS. 1-6 are shown for illustrative purposes only and form no part of the claimed design.
